UNITED STATES PATENT OFFICE.

EDWARD N. JACOBI, OF MILWAUKEE, WISCONSIN, ASSIGNOR TO BRIGGS AND STRATTON CORPORATION, OF MILWAUKEE, WISCONSIN, A CORPORATION OF DELAWARE.

LOCK.

Application filed August 8, 1928. Serial No. 298,293.

This invention relates to certain new and useful improvements in lock structures and has as a general object the provision of an improved lock having a reduced number of 5 parts to generally simplify the assembly and reduce the manufacturing costs.

Another object of this invention resides in the provision of an improved lock structure having a locking bolt stamped from sheet 10 metal rather than machined to simplify its manufacture and provide a strong unitary arrangement.

Another object of this invention resides in the provision of an improved lock having 15 a one piece casing and a locking bolt so arranged that its entire thickness resists shearing stresses inflicted thereon by attempts to drive the cylinder through its mounting head.

Another object of this invention resides 20 in the provision of an improved lock structure in which the locking bolt is constructed and mounted to permit engagement of its spring therewith at its center whereby 25 the maximum strength of the spring is obtained.

A further object of this invention resides 30 in the provision of an improved lock having a one piece mounting barrel provided 35 with a steel front to prevent breaking of the barrel to facilitate its unauthorized removal.

And a still further object of this invention resides in the provision of an improved 35 lock structure which may be readily removed and taken apart without special tools and without injuring the structure in any manner.

With the above and other objects in view 40 which will appear as the description proceeds, my invention resides in the novel construction, combination and arrangement of parts substantially as hereinafter described and more particularly defined by the appended claims, it being understood that 45 such changes in the precise embodiment of the herein disclosed invention may be made as come within the scope of the claims.

In the accompanying drawing, I have illustrated one complete example of the physical embodiment of my invention constructed according to the best mode I have so far devised for the practical application of the principles thereof, and in which:

Figure 1 is a side elevational view, with

parts broken away and in section, of a lock 55 embodying my invention;

Figure 2 is an end elevational view of the lock assembly;

Figure 3 is a fragmentary view of the rear end of the lock with the mounting head in 60 section and the cylinder and locking bolt in side elevation, illustrating the manner of assembling the lock;

Figure 4 is a fragmentary, elevational view looking on the plane of the line 4—4 65 of Figure 1 and illustrating the elongated irregular shaped opening through which the locking bolt is inserted in assembling and

Figure 5 is a perspective view of the inner end of the lock cylinder, locking bolt 70 and the washer member adapted to be positioned between the locking bolt and lock cylinder.

Referring now more particularly to the accompanying drawing, in which like numerals designate like parts throughout the several views, 5 represents a lock cylinder mounting head which is centrally bored from the rear, as at 6, and has its outer end 7 provided with a smaller bore 8 concentric with 75 the bore 6. A lock cylinder 9 is rotatable in the bore 6 and has a reduced outer end portion 10 which is received in a protecting end cap 11 rotatable in the reduced bore 8, the cap 11 having an annular flange 12 on 80 its inner peripheral edge to abut a shoulder 13 formed at the junction of the bores 6 and 8 to prevent outward movement of the lock cylinder.

The lock cylinder is provided with a plurality of spring pressed tumblers 14 which are normally spring urged into longitudinal slots 15 in the walls of the mounting head bore to restrain the cylinder against rotation, the tumblers being retractible within 95 the circumference of the cylinder upon the insertion of a proper key 16 in the usual key opening 17 extended therethrough.

Rotation of the cylinder by the key 16 operates to retract or extend a locking bolt 18 100 beyond the periphery of the mounting head, the locking bolt preferably consisting of a stamping having its locking end slidable in a recess 19 in the wall of the head in communication with the rear end of the bore 6. A shoulder 20 abuts the wall of the bore 6 to limit the outward movement of the bolt by 105 an expansile spring 21 confined between two

spaced guide parts 22 on the inner end of the locking bolt with one end engaging a tit or enlargement 23 formed on the bolt and its other end engaged in a removable cup 24 secured in a recess 25 in the wall of the bore 6 diametrically opposite the recess 19.

The inner end of the cylinder has a substantially V or segmental shaped extension 26 from one end of which a cam 27 projects 10 to engage a shoulder 28 at the inner end of one of the guide parts 22 so that when the cylinder is rotated in a clockwise direction, looking at the front end of the lock, the cam 27 bears against the shoulder 28 to retract 15 the bolt against its spring 21, one guide part working in the cut-away portion 29 of the lock cylinder and the other working on the outer face of the V or segmental shaped extension 26. To prevent the insertion of an 20 instrument through the key opening 17 to work the locking bolt against its spring 21, a washer 30 is positioned between the cylinder and locking bolt. The halves of the 25 washer 30 are on different planes so that one half 31 engages the extension 26 and the other half 32 engages the cut-away section 29 and closes the key opening at its rear, a recess or cut-away portion 33 in the washer member permitting the projection therewith past 30 of the eccentric pin 27.

In assembling the lock, the cylinder is engaged in the mounting head bore from the rear, the washer 30 is then inserted to engage the rear end thereof and the locking bolt unit is passed through an irregular shaped opening 34 in the wall of the mounting head opposite the opening 19 and the spring 21 and its cap 24 are then placed in position, in the manner illustrated in Figure 3, the tit 35 on the bottom of the cup 24 nesting in the opening 34. In assembling or disassembling the lock, a screw driver or other tool 36 is employed in the manner illustrated in Figure 3, disassembling being 40 accomplished by prying the tit 35 of the cup 24 out of the opening 34, as will be readily apparent. The opening 34, as best shown in Figure 4, has its two ends on different planes so as to accommodate the irregular 45 shape of the enlarged inner end of the lock bolt.

What I claim as my invention is:

1. In a lock, a lock cylinder mounting head having a central bore, a rotatable lock cylinder inserted in the mounting head bore from the rear, means preventing movement of the cylinder beyond the mounting head outer end, a locking bolt adapted to be mounted in the mounting head rearwardly 55 of the cylinder after it has been inserted therein, the locking bolt preventing rearward movement of the cylinder, and means whereby rotation of the cylinder actuates the locking bolt.

65 2. In a lock, a lock cylinder mounting

head having a central bore, a rotatable lock cylinder adapted to be inserted in the mounting head bore from one end, means preventing movement of the cylinder beyond the other end of the mounting head, a locking bolt mounted adjacent the first-mentioned end of the mounting head and preventing movement of the cylinder outwardly of the mounting head, means whereby rotation of the cylinder actuates the locking bolt, 70 and means detachably maintaining the locking bolt in position.

3. In a lock, a lock cylinder mounting head having a central bore, a lock cylinder rotatable in the bore, a locking bolt mounted 75 adjacent one end of the cylinder, means whereby rotation of the cylinder moves the locking bolt in one direction, means yieldably urging the locking bolt in the other direction, and means readily detachably 80 maintaining the locking bolt assembled with the mounting head.

4. In a lock, a lock cylinder mounting head having a central bore and a transverse slot communicating with the bore, a lock 90 cylinder rotatable in the bore, a locking bolt slidably mounted in the transverse slot and preventing axial movement of the lock cylinder, means yieldably urging the locking bolt to its operative position with a part 95 thereof extended beyond the periphery of the mounting head, and means whereby rotation of the lock cylinder retracts the locking bolt within the mounting head.

5. In a lock, a lock cylinder mounting 100 head having a central bore and a transverse slot communicating with the bore, a lock cylinder rotatable in the bore, a locking bolt slidably mounted in the transverse slot and adapted to be inserted therein from one 105 end, means limiting outward movement of the locking bolt, means readily detachably maintaining the locking bolt assembled with the mounting head, and means whereby rotation of the lock cylinder moves the locking 110 bolt.

6. In a lock, a lock cylinder mounting head having a central bore and a transverse slot communicating with the bore, a lock cylinder rotatable in the bore, a locking bolt 115 slidably mounted in the transverse slot and inserted therein from one end, means limiting outward movement of the locking bolt, means yieldably urging the locking bolt outwardly of the mounting head, means readily detachably retaining the locking bolt and its urging means assembled with the mounting head, and means whereby rotation of the lock cylinder moves the locking bolt.

7. In a lock, a lock cylinder mounting 125 head having a central bore with a shoulder adjacent one end thereof, a lock cylinder rotatable in the bore and abutting the shoulder at one end to limit axial movement of the cylinder in one direction, a locking 130

- bolt mounted adjacent the opposite end of the lock cylinder to prevent axial movement of the lock cylinder in the other direction, and means engaging the opposite sides of 5 the locking bolt whereby a maximum force is provided to resist shearing stresses inflicted upon the locking bolt during attempts to drive the lock cylinder through the mounting head.
10. In a lock, a lock cylinder mounting head having a central bore and a transverse slot communicating with the bore, a lock cylinder rotatable in the bore, a locking bolt mounted in the transverse slot with its sides 15 in engagement therewith, means limiting outward movement of the locking bolt in one direction, means engaging the locking bolt at a central point and yieldably urging the same outwardly of the mounting head, 20 and means whereby rotation of the lock cylinder moves the locking bolt against the yieldable action of its urging means.
9. In a lock, a lock cylinder mounting head having a central bore and a slot 25 traversing the bore, a lock cylinder rotatable in the bore, a locking bolt adapted to be mounted in the slot to prevent axial movement of the cylinder, means limiting outward movement of the locking bolt, 30 spring means engaging the locking bolt and normally yieldably urging the same outwardly to its operative position engaging said limiting means, a member engageable with the spring means and the slot to prevent 35 the accidental detachment of the spring means and locking bolt, and means whereby rotation of the lock cylinder moves the locking bolt.
10. In a lock of the character described, 40 a mounting head having a slot traversing the bore, a locking bolt movable in the slot and adapted to be inserted therein from one end, means limiting movement of the bolt beyond the slot other end, spring means normally urging the bolt to its position engaging the limiting means, and means engaging the end of the slot through which the bolt is inserted to prevent outward movement of the spring means and the bolt.
50. 11. In a lock of the character described, a mounting head having a central bore and a slot traversing the bore, a lock cylinder rotatable in the bore, a locking bolt slidably mounted in the slot and adapted to be inserted therein from one end, means limiting the movement of the locking bolt beyond the other end of the slot, an expansile spring engageable with the locking bolt and normally urging the same outwardly of the slot other 60 end, a retaining cup engageable with the other end of the spring and readily detachably positioned to retain the spring and bolt in operative position, and means whereby rotation of the lock cylinder moves the locking bolt against its spring.
12. In a lock, a mounting head having a central bore, a lock cylinder rotatable in the bore and having a key slot extending therethrough, a locking bolt operatively associated with the lock cylinder inner end, and means interposed between the lock cylinder and locking bolt to prevent the insertion of an instrument through the key slot to actuate the locking bolt. 70
13. In a lock, a mounting head having a central bore, a lock cylinder rotatable in the bore and having a key slot extending therethrough, a locking bolt operatively associated with the inner end of the lock cylinder, and a washer member interposed between the end of the lock cylinder and locking bolt to prevent the insertion of an instrument through the key slot to actuate the locking bolt. 75
14. In a lock of the character described, a cylinder mounting head, a lock cylinder rotatably mounted in the head, an approximately Y shaped member transversely slideable in the mounting head adjacent the inner end of the cylinder, the leg of the Y forming a locking bolt adapted to be projected beyond the periphery of the mounting head, 80 guide ways in the mounting head in which the arms of the Y are guided, and means whereby rotation of the cylinder actuates the locking bolt. 85
15. In a lock of the character described, a cylinder mounting head, a lock cylinder rotatably mounted in the head, an approximately Y shaped member transversely slideable in the mounting head adjacent the inner end of the cylinder, the leg of the Y forming a locking bolt adapted to be projected beyond the periphery of the mounting head, 90 guide ways in the mounting head in which the arms of the Y are guided, an expansile spring confined between the arms of the Y shaped member and compressed between the transverse portion of said member and the mounting head to normally yieldably urge 95 the locking bolt outwardly of the mounting head, and means whereby rotation of the cylinder retracts the locking bolt. 100
16. In a lock, a lock cylinder mounting head having a central bore and a slot traversing the bore, a lock cylinder rotatable in the bore and having a cam extended therefrom, a locking bolt stamped from sheet metal mounted in the transverse slot and adapted to be inserted therein from one end, 110 means yieldably urging the locking bolt into engagement with the lock cylinder carried cam, and means readily detachably securing the yielding means in position whereby the locking bolt may be readily removed 115 to permit removal of the lock cylinder from the mounting head, rotation of the lock cylinder moving the locking bolt by means of the cam. 120
17. In a lock, a lock cylinder mounting 125 head having a central bore and a slot traversing the bore, a lock cylinder rotatable in the bore and having a cam extended therefrom, a locking bolt stamped from sheet metal mounted in the transverse slot and adapted to be inserted therein from one end, means yieldably urging the locking bolt into engagement with the lock cylinder carried cam, and means readily detachably securing the yielding means in position whereby the locking bolt may be readily removed 130 to permit removal of the lock cylinder from the mounting head, rotation of the lock cylinder moving the locking bolt by means of the cam.

head having a central bore and a slot traversing the bore, a shoulder partially closing the central bore, a lock cylinder rotatable in the bore and adapted to be inserted 5 therein from one end, the mounting head shoulder preventing outward movement of the lock cylinder, a locking bolt mounted in the slot inwardly of the adjacent end of the lock cylinder to prevent inward movement 10 of the lock cylinder, the locking bolt being inserted in the slot from one end thereof, cooperating means carried by the lock cylinder and the locking bolt and normally in engagement whereby rotation of the lock 15 cylinder moves the locking bolt, and means yieldably and readily detachably in engagement with the lock cylinder carried part whereby the entire mechanism may be disassembled by releasing the detachable means 20 to permit the removal of the locking bolt from the slot and the lock cylinder from the central bore.

18. In a cylinder lock, a supporting member, a key controlled cylinder movable in the supporting member, a locking bolt stamped 25 from sheet metal and operable by the cylinder and mounted within the supporting member in the path of removal of the cylinder, and means whereby the locking bolt holds the cylinder in proper assembled position with the supporting member. 30

19. In a cylinder lock, a mounting member, a cylinder movable in the mounting member, a stamped metal locking bolt removably carried by the mounting member in the 35 path of removal of the cylinder and adapted to be actuated by movement of the cylinder, and cooperating means between the locking bolt and mounting member to secure the cylinder in the mounting member. 40

In testimony whereof I have hereunto affixed my signature.

EDWARD N. JACOBI.
